ART OF CRACKING HYDROCARBONS

Filed Oct. 11, 1928

UNITED STATES PATENT OFFICE

HORACE K. ROGERS, OF CHICAGO, ILLINOIS, ASSIGNOR TO SINCLAIR REFINING COMPANY, OF NEW YORK, N. Y., A CORPORATION OF MAINE

ART OF CRACKING HYDROCARBONS

Application filed October 11, 1928. Serial No. 311,744.

This invention relates to improvements in cracking operations carried out to produce lower boiling hydrocarbon oils, such as gasoline, from higher boiling hydrocarbon oils, such as kerosene, gas oil and the like; more particularly the invention relates to improvements with respect to the recovery of lower boiling hydrocarbon oils, such as gasoline, from gas mixtures produced in such cracking operations.

The usual cracking operations involve the production not only of the desired low boiling hydrocarbon oils but also of gases incondensable except under high pressures and at low temperatures. As a consequence, when the desired product is condensed from the gas-vapor mixture from the cracking operation, constituents of the mixture suitable as components of the desired product are carried off uncondensed with the incondensable gases. This invention provides an improved method of recovering such low boiling constituents from such gas mixtures. In the manufacture of gasoline, it has been common practice for some time to subject the raw gas-vapor mixture from the cracking operation to a fractionating operation to produce directly a gasoline product of the desired boiling range, separating in the fractionating operation all constituents higher boiling than suitable as components of this gasoline product. This invention is of special value and application in connection with such operations, but it is also useful in connection with cracking operations which do not include such fractionating operations.

According to the present invention, low boiling but condensable constituents are separated from the gas mixtures produced in cracking operations by absorption in an absorbent menstruum and these absorbed constituents are vaporized from the absorbent menstruum, to be condensed and recovered, by heat supplied at least in part from the cracking operation but, instead of bringing the absorbent menstruum into direct contact with the gas-vapor mixture from the cracking operation as in some previous practices, this heat exchange to effect this vaporization is carried out indirectly and without direct

contact between the gas-vapor mixture from the cracking operation and the absorbent menstruum. A number of advantages are thus secured. The burden of stripping higher boiling constituents of the desired product from the absorbent menstruum absorbed therein during that part of the operation intended to effect vaporization of absorbed constituents rather than further absorption, for example, is avoided. Where the heat to effect the vaporization of absorbed constituents from the absorbent menstruum is supplied from the cracking operation, this feature of the invention represents an important improvement in making the heat supplied to the cracking operation more usefully available in the cracking operation proper. Also, according to this invention, this heat exchange is effected at a point from which heat is not usually usefully returned to the cracking operation proper but from which it is usually rejected, for example to water as a condensing agent. The invention is of special value and application in connection with cracking operations in which the gas-vapor mixture from the cracking operation is subjected to a fractionating operation to produce directly a product of the desired boiling range because, for one reason, the stripping burden just mentioned is materially increased in such operations.

The invention will be further described in connection with the accompanying drawings, which illustrate, diagrammatically and conventionally, one form of apparatus adapted for carrying out the process of the invention. It is intended and will be understood that this more detailed description and illustration are by way of exemplification; different types of apparatus may be used to carry out the various steps carried out in the apparatus illustrated, the process of the invention is useful in connection with types of cracking operations other than that carried out in the particular cracking apparatus illustrated, and the process of the invention may be used in connection with one or several cracking units.

The cracking still illustrated is of the general type described and illustrated in United

States Letters Patent No. 1,285,200, granted November 19, 1918, to the Sinclair Refining Company on the application of Edward W. Isom. This still comprises a bulk supply tank located away from a battery of vertical heating tubes arranged in a furnace, and connections and a circulating pump for circulating oil from the bulk supply tank upwardly through the heating tubes and back to the bulk supply tank. Vapors and gases escape from the bulk supply tank to a reflux tower from which gases and vapors remaining uncondensed escape through connection 1. Raw oil is supplied to the upper end 15 of the reflux tower and through the bearings of the circulating pump. Residual oil or tar is discharged through connections 2. A number of similar cracking stills may be similarly connected to connection 1 through the 20 branch connection shown. For the production of gasoline or gasoline character distillates from gas oil or gas oil character raw stocks, stills of this type are operated under pressures up to 90 to 125 pounds per square 25 inch or somewhat more and with lighter charging stocks, such as kerosene character stocks, higher pressures up to 300 pounds per square inch or more are used.

The invention is also useful in connection 30 with other types of cracking operations carried out in other types of cracking apparatus, such as those in which the oil to be cracked is heated to a cracking temperature in the vapor phase at either approximately atmospheric pressure or at higher pressures and processes in which the oil is heated to a cracking temperature, usually under very high pressures, without complete separation of vapors and unvaporized liquids in the cracking 35 operation itself.

The vapors and gases from the cracking operation, whether carried out in a cracking still of the type illustrated or in other apparatus, are introduced at an intermediate 40 point into the fractionating tower 3 through connection 1. This fractionating tower may be of conventional "bubble" tower construction or of other construction adapted to provide close fractionation. By introducing the 45 gas-vapor mixture at an intermediate point, opportunity is provided for the stripping of all low boiling components from the condensate produced in the tower, and any associated oil components, below the point of introduction of the gas-vapor mixture. A heating medium, steam for example, may also be introduced into the lower end of the tower through connection 4 to promote this stripping action or to assist in control of the 50 tower. The fractionating operation proper may be controlled by introducing into the upper end of the tower, through connection 5, a suitable refluxing medium such as a part of the distillate product or a fraction of corresponding character. The condensate pro-

duced in the tower, and any associated oil components, are discharged through cooler 6 and connection 7. The gases and vapors remaining uncondensed escape through connections 8 and 9. This fractionating tower 70 may be omitted and the gas-vapor mixture from the cracking operation supplied directly to connection 9, but, as previously mentioned, the invention is of special value and application in connection with operations including a fractionating operation such as is 75 carried out in tower 3.

From connection 9, the gas-vapor mixture, including the vapors of the desired product, passes successively through the heat exchanger 10 and the condenser 11. This heat exchanger may be of any conventional construction. In carrying out the invention, a part of the vapors may be condensed from the gas-vapor mixture in this heat exchanger. 80 The condenser 11 discharges into the receiver 12 in which the condensate is separated from the gases and vapors remaining uncondensed. The condensate is discharged through connection 13 and the remaining gas-vapor mixture escapes through connection 14 to the 85 lower end of the scrubbing tower 15.

In the apparatus illustrated, the pressure on the still system may be regulated and reduced by valves between the still and the condenser, for example by valves 16, 17 or 18, or by valves beyond the condenser. Where the condensation is carried out under pressure and the condensate is initially collected under pressure, it is sometimes advantageous to 90 discharge the condensate into another receiver in which the pressure is reduced and from which any liberated gases and vapors are conducted together with the gas and vapor mixture remaining uncondensed under pressure 95 to the scrubbing treatment. In carrying out the invention in connection with pressure distillation operations, a part of the still pressure may be employed to force the gas-vapor mixture through the scrubbing tower. 100 The pressure, for example, may be reduced at a point either between the pressure still and the condenser or beyond the condenser to a point sufficiently above atmospheric pressure 105 to effect this end. The circulation of the gas-vapor mixture through the scrubbing tower may also be effected by a blower, such as is indicated at 19, or the gas-vapor mixture may be drawn through the scrubbing tower by 110 means of an exhauster, such as is indicated 115 at 20.

The scrubbing tower 15 may be of any conventional construction, for example it may be a tower of conventional construction, fitted interiorly with suitable means 120 to promote distribution and contacting of the gas-vapor mixture and the absorbent menstruum. Other refinery gas mixtures, including similar absorbable constituents, coke 125 still tail gases for example, may be supplied 130

to the scrubbing tower 15 through connection 21.

An absorbent menstruum is supplied to the scrubbing tower 15 through connection 22. The absorbent menstruum containing constituents absorbed from the gas-vapor mixture supplied to the scrubbing tower is passed, by means of connections 23 and 24 and pump 25, to the heat exchanger 10, in indirect heat exchanging relation with the vapors supplied through connection 9, and then introduced at an intermediate point into the stripping tower 26 through connection 27. This stripping tower may be of conventional "bubble" tower construction. By introducing the charged absorbent menstruum at an intermediate point, opportunity is provided for the stripping of all absorbed low boiling components from the absorbent menstruum below the point of introduction. The stripped absorbent menstruum is discharged through cooler 28 and connection 29 again to be supplied to the scrubbing tower through connection 22. A heating medium, steam for example, may also be introduced into the lower end of the tower through connection 30 to promote this stripping action or to assist in control of the tower. A cooling medium may also be circulated through the upper end of the tower, through the cooling coil 31 for example, to assist in control of the tower. The constituents absorbed in the scrubbing tower 15 and vaporized from the absorbent menstruum in the stripping tower 26 escape from the upper end of the stripping tower through connection 32. The gas mixture stripped of constituents absorbed in the scrubbing tower is discharged through connection 33.

The vapors escaping through connection 32 may be subjected to condensation with the vapors forming the desired product or they may be condensed separately. In the apparatus illustrated, these vapors may be passed through the heat exchanger 10 to the condenser 11, together with the vapors supplied through connection 8, or a separate condenser 34 and receiver 35 may be provided and these vapors may be passed through this condenser. If a separate condenser 35 is used, any gases and vapors remaining uncondensed may be returned through connection 36 to the scrubbing tower 15. The use of a common condenser, however, has several advantages. The apparatus is simplified. The lower boiling constituents separated from the gas mixture in the scrubbing treatment are more easily recovered as a condensate when condensed with higher boiling components of a composite condensate. Where a common condenser is used, however, the vapors from the stripping operation must be supplied through connection 32 under a pressure equalling that of the vapor supplied through connection 8. If the pressure in the fractionating tower 3 exceeds the

pressure in the stripping tower 26, a blower 37 may be provided to effect this purpose.

In carrying out the invention in the apparatus illustrated, the gas-vapor mixture from the cracking operation proper is first subjected to a fractionating operation to condense therefrom all constituents higher boiling than suitable as components of the desired product in the fractionating tower 3 and the desired product is then condensed from the remaining gas-vapor mixture in the heat exchanger 10 and the condenser 11, the gases and vapors remaining uncondensed are subjected to scrubbing treatment with an absorbent menstruum in the scrubbing tower 15, the absorbent menstruum containing the constituents absorbed in the scrubbing tower 15 is heated by heat exchange with the gas-vapor mixture from the cracking operation in the heat exchanger 10, and the absorbed constituents are vaporized from the thus heated absorbent menstruum in the stripping tower 26 to be condensed, either in the heat exchanger 10 and the condenser 11 or in the condenser 34. The stripped absorbent menstruum is returned from the stripping tower 26 to the scrubbing tower 15 so that it is cyclically circulated in the process. An extraneous absorbent menstruum may be used, or, and this is usually the more advantageous practice, some oil fraction produced in or supplied to the operation, higher boiling than the desired product, may be used as the absorbent menstruum. For example, mineral seal oil or light straw oil may be used as an extraneous absorbent menstruum, or a kerosene character stock or a gas oil character stock, such as is supplied to the cracking operation, or a high boiling fraction produced in the operation, such as the condensate discharged from a fractionating operation preceding condensation of the desired product, may be used as an absorbent menstruum. Where the condensate produced in the fractionating tower 3, for example, or a similar fraction, is used as the absorbent menstruum, any deficiency of the absorbent menstruum may be made up or any excess of the absorbent menstruum may be discharged through the cross connection 38 between connections 7 and 29. The fractionating operation carried out in the tower 3 may be controlled, for example, by the regulated introduction, through connection 5, of a part of the composite cracked product (connection 39 or 40) or a part of the primary condensate alone (connection 40) or a part of the recovered condensates (connection 41) or a similar or suitable fraction may be supplied from some other source (connection 42). The condensate produced in the fractionating tower 3 may be returned to the cracking operation with the raw stock supplied to the cracking operation.

In carrying out the invention to produce

gasoline in the apparatus illustrated, for example, the gas-vapor mixture from the cracking operation proper may be supplied to the fractionating tower through connection 5 1 at a temperature approximating 500-510° F., the gas vapor mixture may escape from the fractionating tower through connection 8 at a temperature approximating 350-360° F., a temperature approximating 295-325° F. 10 may be maintained in the lower end of the stripping tower, the vapors may escape from the stripping tower through connection 32 at a temperature approximating 250-260° F., the charged absorbent menstruum from the 15 scrubbing tower may be heated to a temperature approximating 300-320° F. in the heat exchanger 10, and steam (dry saturated at 150 pounds per square inch) may be supplied through connection 4 at a rate approximating 20 1.1-1.2 pounds per gallon of stripped absorbent menstruum removed with bottom product from the fractionating tower and through connection 30 at a rate approximating 0.1-0.2 pounds per gallon of stripped absorbent 25 menstruum from the stripping tower. It will be understood that these details are intended simply to illustrate one operation embodying the invention.

The invention may advantageously be carried out in conjunction with cracking operations in which a residual oil product is discharged from a pressure distillation operation and expanded at a lower pressure for the separation from tarry or carbonaceous components of the residue of vaporizable oil constituents. In this respect the operation may be carried out, for example, as described in United States Letters Patent No. 1,677,773, granted July 17, 1928, to the Sinclair Refining Company on the application of Eugene C. Herthel & Thomas de C. Tift. In such a combined operation, the condensed overhead product from the expander tower may be supplied to the fractionating tower (the tower 3 in the apparatus illustrated), alone or in conjunction with a part of the condensate produced in condenser 11 or condenser 34, for example, as a control medium, through connections 42 and 5. Such a combined operation may be carried out to produce from gas oil, for example, gasoline, stripped gas and a heavy fuel oil residue, the latter from the expander operation.

The invention may also be carried out in conjunction with a secondary scrubbing treatment of the gas mixture discharged through connection 33 in the apparatus illustrated, for example, as described in United States Letters Patent No. 1,663,868, issued March 27, 1928, to the Sinclair Refining Company on the application of George H. Taber, Jr. In such a combined operation, the recovery operation of the present invention 65 may be substituted for the independent re-

covery operation, that including the first scrubbing treatment, there described.

Referring particularly to the apparatus illustrated, for the purpose of exemplification however, a single recovery system embodying the invention such as that illustrated may be connected to a battery of cracking stills; a battery of pressure stills such as that illustrated, for example, may be similarly connected to connection 1 through a header connection 43. 70 75

I claim:

1. In cracking operations for the production of lower boiling hydrocarbon oils from higher boiling hydrocarbon oils, the improvement which comprises taking off a gas-vapor mixture from the cracking operation including vapors of the desired product, condensing the desired product therefrom, subjecting the gases and vapors remaining uncondensed to scrubbing treatment with an absorbent menstruum to absorb therein condensable constituents of the gases and vapors, passing the absorbent menstruum containing absorbed constituents from the scrubbing treatment in indirect heat exchanging relation with the gas-vapor mixture from which the desired product is condensed, vaporizing absorbed constituents from the thus heated absorbent menstruum while preventing direct contact between the gas-vapor mixture from the cracking operation and the absorbent menstruum and condensing these vaporized constituents. 80 85 90

2. In cracking operations for the production of lower boiling hydrocarbon oils from higher boiling hydrocarbon oils, the improvement which comprises taking off a gas-vapor mixture from the cracking operation including vapors of the desired product, condensing the desired product therefrom, subjecting the gases and vapors remaining uncondensed to scrubbing treatment with an absorbent menstruum to absorb therein condensable constituents of the gases and vapors, passing the absorbent menstruum containing absorbed constituents from the scrubbing treatment in indirect heat exchanging relation with the gas-vapor mixture from which the desired product is condensed, vaporizing absorbed constituents from the thus heated absorbent menstruum while preventing direct contact between the gas-vapor mixture from the cracking operation and the absorbent menstruum and subjecting these vaporized constituents to condensation with the gas-vapor mixture from which the desired product is condensed. 100 105 110 115 120

3. In cracking operations for the production of lower boiling hydrocarbon oils from higher boiling hydrocarbon oils, the improvement which comprises taking off a gas-vapor mixture from the cracking operation including vapors of the desired product and subjecting it to a fractionating operation to con- 125 130

- dense therefrom all constituents higher boiling than suitable as components of the desired product, condensing the desired product therefrom, subjecting the gases and vapors remaining uncondensed to scrubbing treatment with an absorbent menstruum to absorb therein condensable constituents of the gases and vapors, passing the absorbent menstruum containing absorbed constituents from the scrubbing treatment in indirect heat exchanging relation with the gas-vapor mixture from which the desired product is condensed, vaporizing absorbed constituents from the thus heated absorbent menstruum while preventing direct contact between the gas-vapor mixture from the cracking operation and the absorbent menstruum and condensing these vaporized constituents.
4. In cracking operations for the production of lower boiling hydrocarbon oils from higher boiling hydrocarbon oils, the improvement which comprises taking off a gas-vapor mixture from the cracking operation including vapors of the desired product and subjecting it to a fractionating operation to condense therefrom all constituents higher boiling than suitable as components of the desired product, condensing the desired product therefrom, subjecting the gases and vapors remaining uncondensed to scrubbing treatment with an absorbent menstruum to absorb therein condensable constituents of the gases and vapors, passing the absorbent menstruum containing absorbed constituents from the scrubbing treatment in indirect heat exchanging relation with the gas-vapor mixture from which the desired product is condensed, vaporizing absorbed constituents from the thus heated absorbent menstruum while preventing direct contact between the gas-vapor mixture from the cracking operation and the absorbent menstruum and subjecting these vaporized constituents to condensation with the gas-vapor mixture from which the desired product is condensed.
5. In cracking operations for the production of lower boiling hydrocarbon oils from higher boiling hydrocarbon oils, the improvement which comprises taking off a gas-vapor mixture from the cracking operation including vapors of the desired product, condensing the desired product therefrom, subjecting the gases and vapors remaining uncondensed to scrubbing treatment with an absorbent menstruum to absorb therein condensable constituents of the gases and vapors, passing the absorbent menstruum containing absorbed constituents from the scrubbing treatment in indirect heat exchanging relation with the gas-vapor mixture from which the desired product is condensed, vaporizing absorbed constituents from the thus heated absorbent menstruum while preventing direct contact between the gas-vapor mixture from the cracking operation and the absorbent menstruum.

struum, condensing these vaporized constituents, and returning the absorbent menstruum to the scrubbing treatment.

In testimony whereof I affix my signature.

HORACE K. ROGERS. 70
